SLIDING CAR DOOR

George R. Treptow, Chicago, Ill., assignor to The
Youngstown Steel Door Company, Cleveland,
Ohio, a corporation of Ohio

Application September 14, 1940, Serial No. 356,765

16 Claims. (Cl. 20—26)

This invention relates to sliding car doors and primarily to door constructions for preventing rain, snow, dust, cinders and the like from entering the car.

It is an object of this invention to provide sliding doors for cars, particularly of the house type, so constructed and associated with the car wall as to substantially exclude the entry of rain, snow, dust, cinders and the like from these cars.

A further object is to provide sliding car doors having substantially rigid parts and to associate said parts with substantially rigid members on a car wall to prevent the ingress of foreign matter into the car.

A further object is to provide sliding car doors constructed and associated with the car wall so as to prevent damming of water, snow, dust, cinders and the like directly against the rear edge of the doors.

A further object is to provide sliding car doors, the rear portions of which are constructed and associated with the car wall to present offset transversely extending baffles for trapping and disposing of foreign matter exteriorly of the car.

Other objects of the invention will become clear as the description thereof proceeds.

In the drawing forming part of this specification:

Fig. 1 is a fragmentary elevation of a house car and a sliding door thereon embodying the invention.

Fig. 2 is a horizontal section taken on line 2—2 of Fig. 1.

Figs. 3, 4, 5, 6, 7 and 8 are horizontal sections similar to Fig. 2 illustrating other embodiments of the invention.

Referring to the drawing and particularly to the embodiment of the invention illustrated in Figs. 1 and 2, the reference numeral 10 designates generally a metallic sliding door for a railway house car, a portion of the wall of which is shown at 11. The construction of the rear portion of the door, the balance of the structure of which is not essential to the description of the instant invention, embodies a metallic panel 12 having horizontal corrugations one of which is illustrated at 13. The panel is offset outwardly as indicated at 14 to provide a flange 15 spaced laterally outwardly of the main plane of the panel.

A relatively sturdy angular reinforcing member 16 is utilized to reinforce the rear portion of the door 10. The reinforcing member 16 embodies a vertical flange 17 overlapping and secured to the flange 15 of the metallic panel. A flange 18

extends inwardly from the flange 17. The reinforcing member 16 is then terminated rearwardly in the form of a flange 19 disposed substantially in the main plane of the panel. From the flange 19 a flange 20 lying at substantially a right angle to the wall 11 is directed inwardly across the main plane of the panel.

A backing plate 21 extends across the space between the outwardly offset portion 14 of the panel and the inwardly directed flange 18 of the reinforcing member. This plate is secured to the panel substantially in the main plane thereof and to the rearwardly directed flange 19 of the reinforcing member.

Secured to the latter flange of the reinforcing member by means of rivets 22 which fasten the backing plate thereto is a metallic sealing strip 23 which is substantially Z-shaped in section. The sealing strip has a forwardly and inwardly directed flange 24 spaced inwardly from the backing plate 21 and adapted to cooperate with a spark strip 25. The spark strip is adapted to be secured to an outwardly extending flange 26 fastened to the door post 27.

As appears more clearly from Fig. 1 of the drawing the inwardly directed flange 20 of the reinforcing member 16 is bent rearwardly from its normal position so as to provide a flange 28 lying at an obtuse angle to the wall 11. The bending of the flange 20 begins at a point above the bottom of the door so that it serves as a striking member adapted to engage a back stop (not shown) to limit opening movement of the door. Where a back stop is utilized for the upper rear corner of the door the construction of the reinforcing member will be the same as that above described.

A substantially channel shaped member 29 is secured to the post 27. This member comprises a web 30 disposed outwardly and substantially parallel to the wall and oppositely extending flanges 31 and 32. These flanges extend from the web 29 toward the wall and are disposed at an obtuse angle to the wall. The flanges 31 and 32 extending along the wall 11 as indicated at 33 and 34 are fastened thereto in any desired manner. The extension 33 of the flange 31 is bent to provide an outwardly extending flange 35 disposed preferably at a right angle to the wall.

From Fig. 2 of the drawing it will be apparent that the angularity of the flanges 28 and 31 relative to the wall is the same, which is preferred, and that the flange 28 lies forwardly of the flange 31 when the door is closed. The described rela-

tive positions of the flange 28 and 21 is preferred. However, the flange 28 may be disposed rearwardly of the position illustrated so that it will align with the flange 31. It is desirable that the flange 28 should not be positioned rearwardly of the flange 31.

The construction of the reinforcing member 16 and the channel shape member 29 effectively excludes rain, snow, dust, cinders and the like from the car. The flanges 28 and 31 serve as baffles and by reason of their obtuse angularity with respect to the wall avoid damming of foreign matter blown toward the rear edge of the door. Such foreign matter, to the contrary, is directed outwardly so that despite the termination of the flanges 20 and 28 short of the channel shaped member 29 very little foreign matter is blown between these flanges and the channel shaped member. Such foreign matter as may find its way beyond the flanges 20 and 28 will encounter the flange 35 and be prevented from entering the car. The construction thus prevents damming of foreign matter and provides a series of transversely extending baffles which in the preferred construction are offset relative to each other.

In the embodiment of the invention illustrated in Fig. 3 of the drawings an additional baffle is provided. In this embodiment the flange 20 lies substantially at a right angle to the wall throughout its entire height. A separate flange 36 is secured to the flange 20 as by means of welding so as to lie at an obtuse angle to the car wall. The flanges 20 and 36 are braced by means of plates 37 preferably welded to the flanges. By this construction both the flanges 36 and 20 are effective as baffles for preventing the ingress of foreign matter into the car.

In Fig. 4 of the drawing the invention is illustrated applied to a different type of door 38. This door comprises a metallic panel 39 formed with horizontal corrugations, one of which is shown at 40. These corrugations merge into a vertical corrugation 41 beyond which the panel extends as indicated at 42. The vertical corrugation is bridged by means of a backing plate 43 which is secured preferably by means of rivets to the panel on opposite sides of the corrugation. A sealing strip 23 is secured to the inside of the panel extension 42 and is adapted to cooperate with a spark strip 25 as hereinabove described.

A reinforcing member 44 is disposed upon the outside of the panel extension 42 and is fastened thereto and to the sealing strip 23 preferably by means of rivets. The reinforcing member 44 is preferably formed from a structural T and is so disposed that the head flange 45 serves as the attaching flange. The stem 46 of the T extends inwardly toward the car wall 11 and the remaining head flange 47 is deformed so as to lie at an obtuse angle to the wall. The stem 46 and the head flange 47 are braced by means of plates 48 preferably welded to these flanges.

As in the two previously described embodiments of the invention the baffle provided by the stem 46 lies rearwardly of the flange 35 of the channel shaped member 29. Moreover, the relationship between the flanges 46 and 47 of the reinforcing member and the flanges of the channel shaped wall member 29 is substantially the same as the previously described relationship between the reinforcing members and the channel shaped member 29 of the first two embodiments of the invention.

In Figs. 5 and 6 of the drawing the door structures illustrated in Figs. 3 and 4 are shown asso-

ciated with a modified form of wall channel shaped member for preventing the entry of foreign matter into the car.

With particular reference to Fig. 5 of the drawing, it will be seen that the door post 49 differs structurally from the door post 27 and presents a flange 50 extending toward the door opening. An angle member 51 arranged with one of its flanges extending outwardly from the wall is fastened to the door post 49 as by means of rivets 52 passing through the flange 53 of the angle member 51 and the flange 50 of the door post. To the outwardly extending flange 54 of the angle member the post strip 25 is secured. The metallic sheathing 55 of the car wall is fastened to the flange 50 of the door post 49 in any desired manner.

The modified wall channel shaped member 56 is secured to the wall by welding or riveting through its web 57. This web carries a flange 58 adjacent to the door opening and a flange 59 remote from the door opening. The latter flange, as clearly appears from the drawing, extends outwardly at an obtuse angle to the wall. The flange 59 is reinforced by means of plates 60 welded to the web 57 and to the flange. These plates serve additionally as guide ribs for the door to prevent the flange 36 of the door reinforcing member from fouling the flange 59 in the opening movement of the door.

In the form of the invention illustrated in Fig. 6 of the drawing a door post 61 provided with a flange 62 extending rearwardly from the door opening is utilized. To the latter flange the metallic sheathing 63 of the car wall and a post protection angle 64 are fastened as by means of rivets 65. The outwardly extending leg of the post protection angle carries the post strip 25 which is preferably riveted thereto as illustrated.

A channel shaped member 66 substantially similar to the channel shaped member 56 is utilized with the door 38 having the T-shaped reinforcing member 44. The web 67 of the channel shaped member 66 which is somewhat longer than the web 57 of the channel shaped member 56 is secured to the metallic sheathing 63 in any desired manner. The web 67 carries a flange 68 disposed adjacent to the door opening and a flange 69 remote from the door opening. The latter flange lies at an obtuse angle to the car wall. Reinforcing and guiding plates 70 similar to the plates 60 are employed in this embodiment of the invention.

It will be clear from the foregoing description of the embodiments of the invention illustrated in Figs. 5 and 6 of the drawing that they provide flanges which serve to baffle any foreign matter tending to enter the car around the rear edge of the door. The structure of these embodiments, moreover, prevents damming of water or other foreign matter directed toward the rear edge of the door and provides for the disposal of such matter outwardly of the door opening.

The construction illustrated in Fig. 7 of the drawing eliminates the separate channel shaped member 29 utilized in the embodiment of the invention illustrated in Fig. 2 of the drawing. In the considered embodiment the door post 27 is formed with an integral channel shaped portion 71. The web 72 thereof is disposed outwardly of the car wall and is connected to the post by means of the obtusely arranged flanges 73 and 74. A plate member 75 is preferably utilized. This plate member extends across the channel portion 71 and is fastened on opposite

sides thereof in any desired manner. There is thus provided a box section which affords reinforcement for the door post.

An additional baffle comparable to that provided by the outwardly extending flange 35 shown in Fig. 2 of the drawing is employed in the considered embodiment of the invention. This baffle is afforded by the outwardly extending leg 76 of an angle member 77 secured to the door post 27 by riveting or welding. It will be apparent from a cursory comparison of the structures shown in Figs. 2 and 7 of the drawing that the latter secures the same effective baffles as is provided in the former.

A further modification of the invention is illustrated in Fig. 8 of the drawing. This modification utilizes the door post 61 shown in Fig. 6. to the rearwardly extending flange 62 of the door post a modified form of post projection flange 78 is fastened. This angle affords an outwardly extending flange 79 for the securement of the post strip 25. The remaining flange 80 of the post protection angle extends along the wall 11 and is deformed so as to provide a channel shaped portion 81. The web 82 of this portion is offset outwardly from the wall and is connected to the flange 80 by the obtusely disposed flanges 83 and 84. The sheathing 63 of the car wall is disposed between the flanges 62 and 80 and is fastened by the rivets which secure these flanges together.

These rivets are utilized, moreover, to fasten an angle member 85 to the post protection angle. One of the flanges 86 of this member extends outwardly from the wall so as to serve as a baffle.

It will be apparent from the foregoing description of the modifications illustrated in Figs. 7 and 8 of the drawing that the objects of the instant invention are secured by these modifications.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. In a railway house car having a wall provided with a door opening, a vertically extending member on said wall adjacent to the rear of said door opening, and a sliding door mounted upon said wall, said member having a vertical flange extending at a rearwardly facing obtuse angle to said wall, said door having a vertical flange extending toward said wall and said flange of said member at a rearwardly facing obtuse angle to the said wall and terminating short of said flange of said member.

2. In a railway house car having a wall provided with a door opening, a vertically extending substantially channel shaped member on said wall adjacent to said door opening, and a sliding door mounted upon said wall, said channel shaped member having a vertical flange extending at a rearwardly facing obtuse angle to said wall, said door having a vertical flange extending toward said flange of said member at a rearwardly facing obtuse angle to said wall and terminating short of said flange of said member.

3. In a railway house car having a wall provided with a door opening, a vertically extending substantially channel shaped member on

said wall adjacent to said door opening, and a sliding door mounted upon said wall, said channel shaped member having a vertical flange extending at a rearwardly facing obtuse angle to said wall, said door having a vertical flange extending toward said flange of said member at a rearwardly facing obtuse angle to said wall and terminating short of said flange of said member, said channel shaped member having a web spaced from said wall and lying adjacent to said door flange.

4. In a railway house car having a wall provided with a door opening, a vertically extending member on said wall adjacent to said door opening, and a sliding door mounted upon said wall, said member having a vertical flange extending from said wall adjacent to said door opening and a vertical flange extending from said wall remote from said door opening, said latter flange extending at a rearwardly facing obtuse angle to said wall, said door having a vertical flange extending toward said latter flange at a rearwardly facing obtuse angle to said wall and terminating short of said latter flange, said door flange being positioned rearwardly of said first-mentioned flange of said member.

5. In a railway house car having a wall provided with a door opening, a vertically extending substantially channel shaped member on said wall adjacent to said door opening, said channel shaped member having a web spaced from said wall, a flange adjacent to said door opening extending between said web and said wall and a flange remote from said door opening extending between said web and said wall at a rearwardly facing obtuse angle to said wall, and a sliding door mounted upon said wall, said first mentioned flange of said member extending along said wall toward said door opening and having an outwardly extending leg, said door having a flange lying rearwardly of said leg and extending toward said remote flange of said member at a rearwardly facing obtuse angle to said wall, said door flange terminating short of said remote flange of said member.

6. In a railway house car having a wall provided with a door opening, a vertically extending member on said wall adjacent to said door opening, and a sliding door mounted upon said wall, said member having a vertical flange extending at a rearwardly facing obtuse angle to said wall, said door having angularly related vertical flanges extending toward said flange of said member and terminating short thereof, the more remote of said door flanges from said door opening lying at a rearwardly facing obtuse angle to said wall.

7. In a railway house car having a wall provided with a door opening, a vertically extending member on said wall adjacent to said door opening, and a sliding door mounted upon said wall, said member having a vertical T member, means securing one flange of said T member to said door, the stem and the other flange of said T member extending toward said flange of said wall member and terminating short thereof, the latter flange of said T member lying at a rearwardly facing obtuse angle to said wall.

8. In a railway house car having a wall provided with a door opening, a vertically extending substantially channel shaped member on said wall adjacent to said door opening, said channel

shaped member having a web spaced from said wall, a flange adjacent to said door opening extending between said web and said wall and a flange remote from said door opening extending between said web and said wall at a rearwardly facing obtuse angle to said wall, and a sliding door mounted upon said wall, said first mentioned flange of said member extending along said wall toward said door opening and having an outwardly extending leg, said door having angularly related vertical flanges lying rearwardly of said leg, said angularly related flanges extending toward said remote flange of said member and terminating short thereof, the more remote of said angularly related door flanges from said door opening lying at a rearwardly facing obtuse angle to said wall.

9. In a railway house car having a wall provided with a door opening, a vertically extending member on said wall adjacent to said door opening, and a sliding door mounted upon said wall, said member having a body portion and spaced vertical flanges extending outwardly therefrom, the more remote of said flanges from said door opening lying at a rearwardly facing obtuse angle to said wall, said door having a vertical flange extending toward said latter flange of said member at a rearwardly facing obtuse angle to said wall and terminating short of said latter flange.

10. In a railway house car having a wall provided with a door opening, a vertically extending member on said wall adjacent to said door opening, and a sliding door mounted upon said wall, said member having a body portion and spaced vertical flanges extending outwardly therefrom, the more remote of said flanges from said door opening lying at a rearwardly facing obtuse angle to said wall, said door having a vertical flange extending toward said latter flange of said member at a rearwardly facing obtuse angle to said wall and terminating short of said latter flange, said member carrying vertically spaced door guides disposed between said body portion and said latter flange of said member.

11. In a railway house, in combination, a wall provided with a door opening, said wall embodying a door post having a vertical leg, a vertical channel formed in said leg, said channel having an outwardly disposed web and flanges connecting said web with said leg, a plate spanning said channel and secured on opposite sides thereof to said leg, and a sliding door mounted upon said wall, said door having a vertical flange extending toward and terminating short of said web, the flange of said channel remote from said door opening and said door flange lying at a rearwardly facing obtuse angle to said wall.

12. In a railway house car, in combination, a wall provided with a door opening, said wall embodying a door post having a vertical leg, a vertical channel formed in said leg, said chan-

nel having an outwardly disposed web and flanges connecting said web with said leg, and a sliding door mounted upon said wall, said door having a vertical flange extending toward and terminating short of said web, the flange of said channel remote from said door opening and said door flange lying at a rearwardly facing obtuse angle to said wall.

13. In a railway house car, in combination, a wall provided with a door opening, said wall embodying a door post having a vertical leg, a vertical channel formed in said leg, said channel having an outwardly disposed web and flanges connecting said web with said leg, an angular member secured to said leg between said door opening and said channel, said member having an outwardly extending flange and a sliding door mounted upon said wall, said door having a vertical flange extending toward and terminating short of said web, the flange of said channel remote from said door opening and said door flange lying at a rearwardly facing obtuse angle to said wall.

14. In a railway house car, in combination, a wall provided with a door opening, said wall embodying a door post, an angular member having a vertical leg extending along said wall secured to said door post, a vertical channel formed in said leg, said channel having an outwardly disposed web and flanges connecting said web and said leg, and a sliding door mounted upon said wall, said door having a vertical flange extending toward and terminating short of said web, the flange of said channel remote from said door opening and said door flange lying at a rearwardly facing obtuse angle to said wall.

15. In a railway house car, in combination, a wall provided with a door opening, said wall embodying a door post, an angular member having a vertical leg extending along said wall secured to said door post, a vertical channel formed in said leg, said channel having an outwardly disposed web and flanges connecting said web and said leg, a member secured to said leg between said door opening and said channel, said latter member having an outwardly extending flange, and a sliding door mounted upon said wall, said door having a vertical flange extending toward and terminating short of said web, the flange of said channel remote from said door opening and said door flange lying at a rearwardly facing obtuse angle to said wall.

16. In a railway house car having a wall provided with a door opening, a vertically extending member on said wall adjacent to the rear of said opening and a sliding door mounted upon said wall, said member having a vertical flange extending at a rearwardly facing obtuse angle to said wall, said door having a vertical flange extending toward said wall and said flange of said member and terminating short thereof.

GEORGE R. TREPTOW.
